(No Model.)

W. JOHNSTON.

CAR COUPLING.

No. 350,060.

Patented Sept. 28, 1886.

UNITED STATES PATENT OFFICE.

WILLIAM JOHNSTON, OF MENOMINEE, MICHIGAN, ASSIGNOR TO HIMSELF,
JOSEPH FLESHIEM, AND HENRY O. FIFIELD, ALL OF SAME PLACE.

CAR-COUPING.

SPECIFICATION forming part of Letters Patent No. 350,060, dated September 28, 1886.

Application filed July 30, 1886. Serial No. 209,543. (No model.)

To all whom it may concern:

Be it known that I, WILLIAM JOHNSTON, a citizen of the United States, residing in Menominee, in the county of Menominee and State of Michigan, have invented a new and useful Improvement in Automatic Car-Couplers, of which the following is a specification.

My invention relates to car couplers and bumpers.

10 The object of my invention is to provide an efficient and durable automatic car-coupler of a simple and cheap construction, which may be easily operated from the top or side of the cars without going between them in coupling and uncoupling, which may be used in connection with the common link-and-pin coupling now so generally in use in case the cars to be coupled together should not both be furnished with my improved coupler, which will 15 operate to automatically couple the cars together when they are butted against each other, and which at the same time may be easily set so as not to act automatically whenever it is desired simply to push a car or cars along as 20 is commonly done in switching, &c.

To this end my invention consists, essentially, in a pair of coupler or bumper bars on adjoining ends of two cars, which fit by or alongside each other, and each of which are 25 provided with a pivoted coupling-link of the ordinary form, and also with a cam-locking projection adapted to automatically raise the free end of the coupling-link on the opposite bumper bar, so that it will pass over and engage said locking projection. In this way the coupling-link on each bar engages the cam-locking projection on its companion bar, and the adjoining ends of the two links fit between the two cam-locking projections. Each of 30 the bumper-bars is furnished with an operating-lever or pivoted plate, having a ledge occupying the space between the locking projections, and upon which the ends of the coupling-links rest, so that by raising either one of these 35 operating-levers both the coupling-links will be raised and disengaged from the notches or locking projections on the bumper-bars. The operating levers may be raised from the top of the car by a connecting-chain and lever, or 40 from the side of the car by an operating-shaft having a cam projection thereon. This shaft

and its cam are also adapted to hold the operating-lever in an elevated position, and the end of the operating-lever is furnished with an inclined or cam face, so that when so held it 55 will serve to prevent either of the coupling-links engaging the notches or locking projections on the bumper-bars when it is desired to simply push the cars without coupling them together. Each of the bumper-bars is also 60 provided with a hook on its lower edge adapted to fit inside the ordinary coupling-link used on ordinary cars for the purpose of connecting a car provided with my coupler with a car provided with the ordinary coupler when desired. The head of this hook is of sufficient 65 length, so that when the pin is inserted through the link the link cannot become disengaged from the hook.

In the accompanying drawings, which form 70 a part of this specification, and in which similar letters of reference indicate like parts, Figure 1 is a side elevation of a device embodying my invention. Fig. 2 is a similar view showing the position of the parts as the 75 two couplers approach each other. Fig. 3 is a similar view showing the bumper or coupler bars with the coupling-links almost in position for engagement. Fig. 4 is a similar view showing the coupling-links raised by the operating-lever. Fig. 5 is a plan view showing the links 80 engaged. Fig. 6 is a section on line 66 of Fig. 2; and Fig. 7 is a view showing the method of coupling my device with a car furnished with the ordinary link-and-pin coupling.

In said drawings, A represents the car, B the bumper or coupler bars, each of which is furnished with an offset, b, and a locking projection or notch, b', having a curved or inclined upper face, b''. The offset b in the 90 coupler-bars adapts them to fit by each other or alongside of each other side by side, as indicated in Fig. 5. The ends b³ of the bars B are made square, as indicated in the drawings, and, fitting against the shoulders or offsets in 95 said bars, serve as bumpers. Each of the bars B is provided with a coupling-link, C, pivoted in a suitable notch or hole, c, in the coupler-bar B. These coupling-links rest upon the flat upper face of the coupler-bars, and the 100 opening of the link projects over the offset b in the coupler-bar or the space occupied by

the end of the opposite coupler-bar when the same are brought into locking position, as in Figs. 1 or 5. Each of the coupler-bars B is also furnished with a recess, b^4 , in its upper face, in which rests a projection or ledge, d , on the operating-lever D. The lever D is pivoted at d' to the coupler-bar B, and it is raised by a cam, E, on the shaft E', which projects to the side of the car, and which is furnished with an operating wheel or handle, E'; or it may be operated from the top of the car by a chain, F, and bent lever F'. The ledge d on each of the operating-levers D projects just across the upper face of the bars B, resting in the notches b^4 . The length of the ledges d should about equal the space between the locking-projections $b^1 b^2$ when the two coupler-bars are brought into interlocking position, as indicated in Figs. 1, 4, and 5. By this means the ends of both links CC will rest upon each of the ledges d , so that if either operating-lever D D is elevated both links will be simultaneously disengaged from the notches or locking-projections $b^1 b^2$ on the coupler-bars B B.

Each of the coupler-bars B B is also provided with a flat spring, B', the free end of which rests upon and presses against the link C and serves to hold it down or in place. Each of the operating-levers D is furnished with an inclined end, d^2 , which, when elevated into the position indicated in Fig. 4, serves to continue the inclined end b^2 of the coupler-bar B, so that the link C on the opposite coupler-bar will ride thereon, as indicated in said Fig. 4, and thus prevent both links CC from engaging the notches or locking projections $b^1 b^2$ when either of said operating-levers is raised. The cam E, when turned a little past its center, as indicated in Fig. 4, will serve to hold the operating-lever in its elevated position when it is desired to simply push the cars along without coupling them together.

e is a stop or pin to limit the movement of the cam E, and e' is a similar stop or pin to limit the movement of the operating-lever D. Each of the coupler or bumper bars B B is furnished with a long hook, B², for receiving one end of an ordinary coupling-link when it is desired to connect the car with a car furnished with the ordinary link-and-pin coupling. The hook B² is made long enough so that when inserted in the link and the ordinary coupling-pin is also inserted in the link the hook cannot become disengaged from the link, as indicated in Fig. 7.

In operation, as the cars approach each other, the ends of the bars B B pass each other, and the inclined or cam faces $b^2 b^2$ raise the free ends of the pivoted links CC, as indicated in Figs. 2 and 3, until said links automatically drop over and engage the notches or locking projections $b^1 b^2$. To uncouple the cars, the operator simply raises one lever D from one side or the other of the car, or from the top thereof. It will be observed that the shaft E' of one of the cars projects to the right side, while that of the other projects to the left. If it is de-

sired to push the cars together without coupling them, one of the levers D is raised, as indicated in Fig. 4, the cam E being turned sufficiently far to hold the lever in its elevated position.

I claim—

1. The offset combined coupler and bumper bars B B, adapted to fit side by side, having inclined or cam upper faces and locking notches or projections, and provided with pivoted links CC, adapted to ride on said inclined or cam faces and fit over said locking projections, said bars B B having square ends adapted to fit against the corresponding offsets or shoulders in said bars, and serve as bumpers, substantially as specified. 75

2. The offset coupler-bars B B, adapted to fit side by side, having inclined or cam upper faces and locking notches or projections, and provided with pivoted links CC, adapted to ride on said inclined or cam faces and fit over said locking projections, in combination with operating-levers D D, having ledges or projections d , for the ends of said links to rest upon, substantially as specified. 85

3. The offset coupler-bars B B, adapted to fit side by side, having inclined or cam upper faces and locking notches or projections, and provided with pivoted links CC, adapted to ride on said inclined or cam faces and fit over said locking projections, in combination with operating-levers D D, having ledges or projections d , for the ends of said links to rest 95 upon, and operating-shafts E' E', and cams E E, substantially as specified. 100

4. The offset coupler-bars B B, adapted to fit side by side, having inclined or cam upper faces and locking notches or projections, and provided with pivoted links CC, adapted to ride on said inclined or cam faces and fit over said locking projections, in combination with operating-levers D D, having ledges or projections d , for the ends of said links to rest 110 upon, operating-shafts E' E', and cams E E, and chain F F, and levers F' F', substantially as specified. 115

5. The offset coupler-bars B B, adapted to fit side by side, having inclined or cam upper faces and locking notches or projections, and provided with pivoted links CC, adapted to ride on said inclined or cam faces and fit over said locking projections, each of said coupler-bars B B being also furnished with a hook, B², at 120 its lower edge for engagement with the ordinary link-and-pin coupling, substantially as specified.

6. The offset coupler-bars B B, adapted to fit side by side, having inclined or cam upper faces and locking notches or projections, and provided with pivoted links CC, adapted to ride on said inclined or cam faces and fit over said locking projections, in combination with operating-levers D D, having ledges or projections d , for the ends of said links to rest upon, said levers D D having inclined ends adapted to continue the inclined faces of said coupler-bars when said levers are raised and 125 130

thus prevent the automatic engagement of said links, substantially as specified.

7. The offset coupler-bars B B, adapted to fit side by side, having inclined or cam upper faces and locking notches or projections, and provided with pivoted links C C, adapted to ride on said inclined or cam faces and fit over said locking-projections, in combination with springs B' B', substantially as specified.

8. The combination of coupler-bars B B, having offsets b b, the ends of said coupler-bars adapted to abut against said offsets as bumpers, said coupler-bars being furnished

with locking projections or notches b' b', inclined upper faces b² b², coupling-links C C, 15 pivoted to said coupler-bars near their upper edges and adapted to rest on their flat upper faces, operating-levers D D, having ledges d d and inclined ends d² d², said coupler-bars B B being furnished with notches d⁴ d⁴ for said 20 ledges D D to rest in, cam E E, and operating-shafts E' E', substantially as specified.
